UNITED STATES PATENT OFFICE.

JOHN H. STEWART AND JOHN M. SCHENK, OF WATERLOO, IOWA, ASSIGNEES TO
CEMENT TILE MACHINERY COMPANY, OF WATERLOO, IOWA.

FORMER-HEAD FOR SEWER-PIPE MACHINES.

1,177,733.

Specification of Letters Patent.

Patented Apr. 4, 1916.

Application filed July 3, 1914. Serial No. 848,913.

To all whom it may concern:

Be it known that we, JOHN H. STEWART and JOHN M. SCHENK, citizens of the United States of America, and residents of Waterloo, Blackhawk county, Iowa, have invented certain new and useful Improvements in Former-Heads for Sewer-Pipe Machines, of which the following is a specification.

Our invention relates to improvements in former-heads for sewer-pipe machines, and the object of our improvement is to furnish a rotatable or spirally movable former-head adapted to work within a mold-casing, and equipped with forming means for the bell 10 or outwardly offset part of the pipe section to be shaped from cement or concrete in said casing, the forming means for the bell part being so linked and connected to the other parts of the former-head as to be recessive 15 or protrusive to take them out of or into their radii of action without interference. This object we have accomplished by the mechanism which is hereinafter described and claimed, and which is illustrated in the 20 accompanying drawings, in which,

Figure 1 is a vertical axial section of a sewer-pipe mold casing and of our improved former-head as operative therein, with parts broken away. Fig. 2 is a horizontal section 30 of said parts, taken on the line *a*—*b* of Fig. 1, and looking in the direction of the arrow.

Similar numerals of reference denote corresponding parts throughout the several views.

This invention is an improvement upon our device applied for under application Serial Number 817,208.

The numeral 15 denotes a hollow cylindrical mold-casing, provided with an expanded bell head at its lower end, within which may be formed a sewer-pipe of concrete, to be formed by included mechanism as hereinafter described. Said mold-casing rests coaxially upon the hollow cylindrical base-block 17, which latter forms part of the revolving carriage of a tile machine, not shown. A pallet 14 of annular form is seated within the expanded portion of said casing 15, and flanged to close the lower end 40 thereof, the pallet having an offset part extending first upwardly and then inwardly to fit about a cylindrical former-head 1 movable spirally and vertically therethrough, and mounted on the lower end of a shaft 2.

55 The space between the upright part of the

pallet and the expanded part of the casing is that in which the bell shaped flange of the sewer pipe section is to be formed.

The numeral 4 denotes a sleeve extending upwardly from the head 1 and seating the lower end of said shaft 2. This sleeve has integral oppositely directed curved projections 3 to which are detachably and reversibly secured by means of the bolt 6 the curved forming bodies or trowels 5 whose outer parts are in line vertically with the circumferential periphery of the former-head 1. Said sleeve 4 has oppositely projecting integral lugs 8 located intermediately between the projections 3 and orificed 70 transversely to receive the pivot bolts 7 on which are mounted the pairs of arms 9—10, the latter being connected at their outer ends after being brought convergently together by means of the pivot bolts 11. 75

The numeral 16 denotes rods whose lower parts are bent laterally at an angle to their main parts and pivoted at the said angles to the pintles 11. The laterally directed parts 12 of said bars 16 are bent downwardly and rearwardly relative to the direction of rotation of said former-head at 13 as shown, to extend downwardly into the space between the upright part of the pallet 14 and the expanded part of said mold casing 15. The 85 upwardly directed parts 16 are pivotally connected at their upper extremities to lugs 19 depending from a collar 18 which is slidably non-rotatably mounted on the shaft 2.

The numeral 22 denotes a lever, one end 90 of which is pivotally and adjustably mounted at 25 on a fixed bracket or arm 26. Said arm is slotted at 23 to receive a pin 24 projecting from a collar 21 rotatably mounted upon a sleeve 18.

When the lever 22 is raised or lowered, it shifts up and down the sleeve 18 with the pivotally connected rods 16 to swing up or down the arms 10 to thus act upon the troweling parts 12—13 in either elevating 100 them, as indicated by the dotted lines in Fig. 1, to positions located entirely within the outer limit of action of the rotary former-head 1, or to drop said troweling parts to project into the annular interspace 105 around the pallet 14. The working positions of the troweling parts 12—13 are indicated in said Fig. 1 by full lines. When thus projected down into said annular interspace, said troweling parts act in packing by rub- 110

bing the concrete thereinto and against the end closure flange of said pallet to form the outwardly flanged bell of the sewer pipe. The troweling action of the down-turned parts 13 of the arms 12 is facilitated on account of their being directed obliquely rearwardly relative to the direction of rotation of said former-head 1. When the lever 22 is used to swing up the arms 10 and withdraw the said troweling parts, as heretofore described, the former-head 1 with its fixed troweling surfaces 5 moves up spirally to the casing 13 and forms the cylindrical part of the pipe. Any desired means may be used for actuating the former-head 1 to form the pipe within said mold.

Having described our invention, what we claim as new, and desire to secure by Letters Patent, is:

20 1. In combination, a mold-casing having one end expanded in diameter, a pallet closing the expanded end having a raised inner concentric part spaced from the inner wall of said expanded part, and a packing tool 25 within said casing movable into and out of the space between said expanded part and the raised part of the pallet and rotatable therein to pack concrete within said space to form a bell-shaped mouth on a tile formed 30 in said casing.

2. In combination, a mold-casing for hollow tile having one end expanded in diameter, a pallet closing the expanded end of said pallet and having an internal raised 35 wall spaced from the expanded part of said casing to provide an annular end trough therebetween, and a packing arm mounted pivotally within the casing, movable into and out of said end trough to pack the material upon the pallet to compress and consolidate the material at the terminal edge of the bell-shaped end of the tile formed in said casing.

3. In combination, a cylindrical mold-casing having a bell-shaped end, an annular pallet closing said bell-shaped end and having a raised inner wall extended concentrically into said bell-shaped end, a cylindrical former-head movable rotatably and longitudinally through said pallet and casing, and a bent arm connected to said former-head, movable into the space between said bell-shaped end and the raised wall of said pallet and adapted to be retracted from said space above said former-head to lie within the outer limits of said head.

4. In combination, a cylindrical mold-casing, an annular pallet adapted to removably close one end of said casing, a rotatable cylindrical former-head movable longitudi-

nally through said casing, and an arm movably connected to said former-head and movable toward the end of the casing closed by said pallet to pack materials against the closure part of the pallet, said arm being adapted to be retracted into the casing space above said former-head within its outer limits.

5. In combination, a stationary cylindrical mold-casing having a bell-shaped end, an annular pallet fitted over said bell-shaped end, a rotatable former-head movable longitudinally through said pallet fittingly and through said casing spaced concentrically from the inner wall thereof, and a downwardly bent arm movably connected to the top of said former-head and adapted to swing out and down into the bell-shaped end of the casing to pack materials against the end-closure part of the pallet.

6. In combination, a mold-casing with a flaring end, an annular pallet seated in the flaring end of said casing and shaped to cooperate with said flaring end to provide an annular space, a rotatable former-head longitudinally movable through said casing in spaced relation thereto and through said pallet in fitting relation thereto, an arm pivotally connected to the upper part of said former-head, a second arm pivoted to the outer end of said arm and having a downwardly-directed extremity bent rearwardly relative to its direction of revolution into said annular interspace when lowered, and elevated to be withdrawn entirely within the limit of action of the circumferential periphery of said former-head when raised, an upwardly-directed bar integral with the second-mentioned arm, and means for moving said bar up and down to rock said first-mentioned arm vertically.

7. In combination, a hollow mold-casing, means for partially closing one end of said casing adapted, in coaction with the inner wall of the casing, to provide a trough within and about said end, opening into the casing in the direction of its length, and a troweling-tool within said casing, movable into or out of said trough and adapted to be propelled within and along it to trowel material deposited within the trough to form a tile-end therein.

Signed at Waterloo, Iowa, this 18th day of June, 1914.

JOHN H. STEWART,
JOHN M. SCHENK.
